DEODORANT HOLDER OR THE LIKE

Milton Fink, Kewgarden Hills, N. Y.

Application March 31, 1950, Serial No. 8,896

Term of patent 14 years

(Cl. D58—24)

To all whom it may concern:

Be it known that I, Milton Fink, a citizen of the United States, residing at Kewgarden Hills, county of Queens, State of New York, have invented a new, original, and ornamental Design for a Deodorant Holder or the like, of which the following is a specification, reference being had to the accompanying drawing, forming part thereof.

Fig. 1 is a front elevational view of a deodorant holder or the like embodying my new design;

Fig. 2 is a top plan view thereof;

Fig. 3 is a side elevational view of Fig. 1,

Fig. 4 is a side view with the top cup member removed;

Fig. 5 is an elevational view of the said cup member;

Fig. 6 is a cross section taken on line 6—6 of Fig. 2; and

Fig. 7 is a bottom plan view of Fig. 3.

I claim:

The ornamental design for a deodorant holder or the like, as shown.

MILTON FINK.
